COMBINATION HANGER AND CLAMP FOR SUPPORTING ELECTRICAL CONDUCTORS

Albert H. Genter, Mount Lebanon, Pa.

Application May 27, 1948, Serial No. 29,490

2 Claims. (Cl. 191—43)

1

The principal object which I have in view is the provision of a more durable and efficient device for suspending and insulating electrical conductors, such as trolley wires and feed wires, especially in mining and tunneling operations, but applicable also to general use for the overhead support of electrical conductors.

For these purposes my invention provides a device comprising a metallic member provided with means for attaching it to an elevated support, such, for instance, as the roof of a mine or to the roof support, said member being provided with a depending clevis portion, a second member, formed of dielectric or insulating material, which is fitted upwardly into the clevis of the first member and fixedly secured therein, and metallic means secured to and depending from the insulator member and provided at its lower extremity with a portion in which the electrical conductor is held.

The points of attachment between the first member and the insulator member and between the insulator and the means for supporting the electrical conductor are spaced apart so that a sufficient extent of the dielectric material of the insulator member is interposed between such points of attachment to prevent positively the leaking of current between the conductor supporting means and the first mentioned member.

Thus, in the preferred embodiment of the principles of my invention which is illustrated in the drawings, the insulator member consists of an oblong block of insulating material, such as a laminated dielectric plastic with its longer axis disposed at right angles to the depending clevis into which it is fitted, the block being provided with a transverse hole at its longitudinal center which registers with the aligned holes in the legs of the clevis. A rivet or bolt extending through the three registering holes secures the block in place and the flat top surface of the block fits against the flat bottom surface of the bridge of the clevis to hold the block against movement relative to the clevis.

The means for supporting the electrical conductor has substantially the same horizontal length as the insulator block, and it is provided with a bolt hole adjacent each of its ends, which holes register with holes in the insulator member and through which bolts extend to secure the said conductor-supporting means to the insulator block. The intermediate portion of the top edge of the said means intermediate of the bolt holes is dipped downwardly to space said means from the legs of the clevis, thus providing for the

2

proper electrical insulation between the first mentioned member and said conductor-supporting means.

A satisfactory manner of effecting such insulating space is to provide the said conductor-supporting means with upwardly extending pierced ears adjacent its opposite ends to receive the bolts by which it is secured to the insulator member, and to curve the top edge of the insulator member downwardly between the ears to substantially space it from the clevis legs, which legs preferably are of arcuate shape to provide a uniform insulating spacing.

Where my invention is to be employed for the support of a trolley wire, the conductor-supporting means consists of a pair of depending jaw plates bolted at either side of the insulator member and provided with coacting trough portions adjacent to and parallel with their horizontal lower edges, which trough portions coact to grip the wire between them as the bolts securing the jaws to the insulator member are tightened, the ears of said jaws being provided with rounded horizontal ridges on their inner faces above the bolt holes so that the lower edges of the jaws swing toward each other as the bolts are tightened.

Where the hanger clamp is to be used to support a feed wire or the like, the conductor-supporting means is in the form of a single plate provided, as in the case of the jaws, with upwardly extending pierced ears at each end of its upper edge, the intermediate portion of said edge is depressed between the ears, said plate being bolted against one side of the insulator block. The lower edge of the plate is bent or curved inwardly and upwardly to provide a longitudinal shelf in which the conductor is laid, and a bolt extends through a hole in the plate and through a registering hole in the trough adjacent the free edge of the latter to hold the conductor against disengagement from the trough.

Other advantages will appear from the following description.

In the accompanying drawings, wherein are illustrated practical embodiments of the principles of the invention,

Fig. 1 is a side elevation showing the hanger clamp secured to the protruding end of an expansion bolt fixed in a hole bored in the mine roof, and a trolley wire supported by the same;

Fig. 2 is a top plan view of the same with parts

in sections.

3

Fig. 3 is an end view of the same;

Fig. 4 is a side elevation of the hanger clamp showing the latter secured to the under face of a horizontal beam, such as one of the roof-supporting beams of a mine;

Fig. 5 is an end view of the same;

Fig. 6 is a top plan view of the same;

Fig. 7 is a side elevation showing the hanger clamp secured to a vertical face of a mine timber;

Fig. 8 is an end view of the same;

Fig. 9 is a top plan view of the same;

Fig. 10 is a side elevation showing the hanger clamp arranged for supporting an electric conductor, such as a feed wire;

Fig. 11 is an end elevation of the same, and

Fig. 12 is a top plan view of the same with parts in sections.

Referring first to Figs. 1, 2 and 3 of the drawings, 20 indicates a metallic member, which conveniently may be a casting, and which integrally comprises a horizontal plate portion 21 having a flat under surface from either side of which depends a leg 22, the legs and the under surface of the plate constituting a clevis. Extending upwardly from the plate portion 21 is a tubular neck 23 internally threaded to be screwed up on the threaded lower end of a bolt 24 protruding downwardly from an expansion bolt mechanism 25, which latter is fixedly embedded in a hole bored in the mine roof 26.

27 indicates a member or block of suitable electrical insulating material, such for instance as a laminated dielectric plastic, and preferably of rectangular shape. The block 27 fits snugly up between the clevis legs 22 and against the under surface of the plate portion 21, and is secured rigidly in position by means of a fastening member such as the rivet 28 extending through registering holes in the legs and the block.

The block 27 is long enough to extend considerably beyond the ends of the plate portion 21 and adjacent each of its ends the block is provided with a transverse bolt hole, said bolt holes preferably being below the level of the rivet hole in the block.

29 indicates a pair of metallic jaw plates which are bolted on either side of the block 27. At either end the jaws are provided with an upwardly extending ear 30, each ear being pierced with a bolt hole, so that the bolts 31 may be inserted through each set of three registering holes to mount the jaw plates on the block 27.

To avoid leakage of electric current from the jaw plates to the clevis legs 22 the top edge of the jaw plates is curved downwardly intermediate of the ears, thus providing a uniform clearance of relatively great width between the jaw plates and the legs, the edges of the latter being also provided with a similar curvature to maintain a clearance of uniform value.

As shown in Fig. 1 the curve of the top edge of the jaw plates 29 may be deep enough to clear the bottom edge of the insulator block 27.

The ears 30, above their bolt holes, are provided on their inner faces with horizontally extending ribs 32 which bear against the block 27 and space the jaw member from other contact with the block.

The jaw plates 29 extend materially below the block 27 and are bent inwardly toward each other and at their bottom edges are provided with inwardly faced trough portions 33 which grip and securely hold in place the trolley wire 34. The tightening of the nuts on the bolts 31 which secure the jaw plates to the block causes the jaw

4

plates to swing toward each other on their ribs 32 and tightly grip the trolley wire.

In Figs. 4, 5 and 6 I illustrate the attachment of the hanger clamp to the under face of a mine roof timber. The structure is similar to that already described except that the tubular threaded neck is omitted and a longer horizontal plate 35 is employed, said plate is provided with bolt openings 36 at its ends. To mount the hanger clamp in place screw bolts 37 are engaged in the openings 36 and driven up into the timber 38 with the plate 35 fitting flat against the under surface of the timber.

In Figs. 7, 8 and 9 the horizontal flat portion shown at 39 is shortened and from the end of it a vertical plate portion 40 extends upwardly and is provided at its ends with bolt openings 41. The plate portion fits flat against the vertical face of the timber 38 and is fixed thereto by the screw bolts 42.

Referring now to Figs. 10, 11 and 12, I show an adaptation of my hanger clamp to the support of an electric conductor, such as a feed wire. In this instance the jaw plates above described are not used but a single metallic hanger plate 43 is substituted. The plate 43 is bolted to one side of the insulator block 27 by means of the bolts 31 which are inserted through the holes in the ears 30 of the hanger plate 43 and the top edge of the hanger plate intermediate of the ears is curved downwardly to be sufficiently spaced from the clevis legs to insure against current leakage.

The bottom horizontal edge of the hanger plate 43 is bent laterally and upwardly to provide a shelf 44 along which the conductor 45 extends and the vertical portion of the hanger plate 43 and the lip of the shelf 44 are provided with bolt holes in which the angular bolt 46 is inserted, and a nut 47 is screwed up on the threaded end of the bolt to clamp the conductor firmly on and to the shelf.

The bolt hole 48 in the wall of the shelf 44 is open to the edge of the shelf for convenience in inserting the bolt 46 in place and to enable the angular bolt to tightly grip the conductor as the nut is tightened on the bolt.

My improved hanger clamp is less expensive to manufacture than those now in general use, and more durable and reliable. Again it requires less head-room, which is an important consideration in mining operation. It may be used in connection with the standard expansion bolts, and its use simplifies the requirement of accessories employed in stringing feeder and trolley wires.

I claim:

1. In means for supporting an electrical conductor, such as a trolley wire, from an overhead structure, the combination of a plate of insulating material, and provided on its sides with flat vertical side portions, means for supporting said plate from an overhead support, a pair of metal jaw plates mounted one at either side of said insulator plate, and depending below the same, said jaw plates below the insulator plate converging and each being provided at its lower extremity with an inwardly projecting horizontal straight and relatively sharp edge, which edges are arranged to grip the conductor between said jaw plates, the upper ends of said jaw plates being provided on their inner faces with straight horizontal fulcrum beads which bear against the flat faces of the sides of the insulator plate so as to maintain the bodies of said jaw plates out

of contact with said insulator plate, the insulator plate and the jaw plates being provided with registering holes, a bolt with a threaded end extending through said registering holes, and a threaded nut applied to said bolt to cause the 5 lower edges of the jaw plates to move toward each other and firmly engage the conductor from either side to secure the latter in place.

2. The structure of claim 1 characterized by the said beads being of sufficient size to maintain 10 the bodies of the jaw plates out of contact with the flat sides of the insulator plate when the beads are in contact with said plate.
